[57] CLAIM

The ornamental design for a sleepwear hanger, substantially as shown and described.

DESCRIPTION

FIG. 1 is a reduced front perspective view of a sleepwear hanger showing our new design;

FIG. 2 is a front elevational view thereof;

FIG. 3 is a top plan view thereof;

FIG. 4 is a side elevational view taken from the right of FIG. 2;

FIG. 5 is a side elevational view taken from the left of FIG. 2.

The bottom and rear faces of the hanger are not ornamented.

Fig. 5.

Fig. 4.
